UNITED STATES PATENT OFFICE.

ALBERT F. STAPLES, OF DORCHESTER, MASSACHUSETTS.

ASH-SIFTER.

1,108,270.

Specification of Letters Patent. Patented Aug. 25, 1914.

Application filed July 5, 1913. Serial No. 777,487.

To all whom it may concern:

Be it known that I, ALBERT F. STAPLES, a citizen of the United States, and resident of Dorchester, in the county of Suffolk and State of Massachusetts, have invented certain new and useful Improvements in Ash-Sifters, of which the following is a specification.

This invention relates to ash-sifters of the type in which a foraminous body is mounted upon an elongated handle, and so formed that it may be used in the manner of a shovel, to receive and raise a body of ashes to be sifted.

15 The object of the invention is to produce an ash-sifter of simple and convenient form, in which the ashes from a furnace may be sifted within the ash-pit of a furnace, so that all of the dust resulting from 20 the sifting operation is retained within the furnace and carried away by the draft thereof, while only the cinders are withdrawn from the ash-pit and discharged from the sifter. To the foregoing end I 25 employ, in connection with the foraminous body of my sifter, a pivotally mounted device at the forward end of the body, such as has been employed in previously proposed constructions, for the alternative 30 purposes of forming a lip to facilitate the admission of ashes to the body, and an end-closure to retain the ashes therein during the sifting operation. In addition to these parts, however, and to adapt my device to 35 the particular mode of operation for which it is designed, I employ supporting members or legs, which are manually movable into operative or inoperative position, and which, when in operative position, project 40 entirely below the body of the sifter, so that they may rest upon the grating or floor-surface of the ash-pit, and support the foraminous body above such surface and above any ashes thereon. I further omit 45 any such imperforate bottom-member as has been proposed in previous constructions, so that the ashes sifted through the foraminous body may fall directly to the floor-surface of the ash-pit.

50 By the novel construction and arrangement of parts above described, I produce a sifter which may be introduced into the ash-pit of the furnace in the manner of a shovel, being thereby filled with ashes, and which 55 may then be manipulated to raise it clear of the bottom of the ash-pit and support it

in that position, while it is shaken in a horizontal direction, thus sifting out the fine ashes before withdrawing the sifter from the ash-pit, these ashes remaining 60 within the ash-pit, and the dust being carried away by the draft therein.

In the accompanying drawings:—Figure 1 is a perspective view of an ash-sifter embodying the present invention, showing the parts in their normal position; and Fig. 2 is a side-elevation, partly in vertical section, showing the end-wall in the closed position which it occupies during the sifting operation.

70 The invention is illustrated as embodied in a sifter having an elongated handle 3 of which the rear-end is cleft to provide two bifurcations 4 between which a transverse grip 5 is fixed.

75 The body of the sifter has a frame-work of heavy wire, this frame-work comprising substantially parallel wires 6, which support the upper edge of the body, and three substantially parallel wires 7, 8 and 9 at the lower surface of the body. The two wires 6 are shown as formed of a single continuous length, and the wires 7 and 8 are similarly formed, all of these wires, at their rearmost doubled portions, being embraced 80 and fixed within a sleeve 10 which is attached to the forward end of the handle 3. The rear end of the wire 9 is seated between the other wires and also embraced within the sleeve, thus providing a simple and 85 rigid connection between the wires and the handle.

90 Wire-netting 11 suitably formed to rest upon the wires 7, 8 and 9 is attached, at its upper edges, to the wires 6, while the forward edge of the netting is attached to a transverse sheet-metal member 12. This member is bent upwardly, at its ends, to embrace the forward ends of the wires 6, while the forward ends of the wires 7, 8 and 100 9 are looped through openings in the member 12, as clearly shown in the drawings. As the wires 7, 8 and 9 are located entirely beneath the wire-netting they provide surfaces upon which the ash-sifter may slide 105 so as to relieve the netting from friction and wear.

110 A movable end-wall is provided, in the form of a sheet-metal member 13 which is pivoted to the forward edge of the member 12. For the purpose of so connecting these parts they are provided with integral hinge-

sleeves 14 embracing a pivot-rod 15. In the normal position of the parts, as shown in Fig. 1, the wall 13 lies in the same plane as the part 12, so as to form a lip at the forward end of the body which may be readily introduced into or beneath a body of ashes to permit the sifter to act in the manner of a scoop or shovel. The member 13 is bent upwardly at its ends to provide integral 10 side-walls 16, which have portions 17 extending to some distance in the rear.

A yoke-shaped rod 18 is pivoted, at its forward ends, to the side-walls 16, and is supported, at its rear central portion 19, 15 within an eye 20 projecting downwardly from the handle, being free to slide therein. A rod 21 is looped, at its forward end, into the part 19 of the rod 18, while its rear end is looped into a downwardly-projecting arm 20 22 of an operating-lever. This lever is mounted on a transverse pivot 23 in the bifurcated portion of the handle, and it has a rearwardly-projecting arm 24 which may be conveniently grasped together with the grip 25. When the lever is so grasped and is drawn upwardly into a position adjacent the grip 5, as shown in Fig. 2, the swinging movement of the lever causes the rods 21 and 18 to be drawn rearwardly, thus swinging 30 the end-wall 13 upwardly into vertical position, as shown in Fig. 2, and so closing the forward end of the sifter. At the same time the projections 17 are swung into depending position, so that they project to a 35 substantial distance below the bottom of the body. The end-wall is normally retained in depressed position by a spring 25, which is coiled around the rod 15 and has ends engaging the parts 12 and 13 respectively. 40 The sifter just described is used as follows: With the parts in the position of Fig. 1, the user introduces the sifter beneath a body of ashes within any receptacle, such as the ash-pit of a furnace, thus filling the 45 sifter with ashes. He then moves the operating-lever to close the forward end of the sifter and bring the parts to the position of Fig. 2. The projections 17 then project downwardly so as to provide legs by which 50 the weight of the body may be supported upon the bottom of the ash-pit, and the user then shakes the sifter longitudinally, thus shaking out the finer ashes while the cinders are retained within the body by the closed

end-wall. During this operation all of the 55 dust which rises is retained within the ash-pit and carried away by the draft of the furnace. After the sifting operation is completed the user withdraws the sifter from the ash-pit and swings the operating-lever 60 downwardly so as to open the end-wall to normal position, and the cinders may then be discharged from the sifter in the same manner as from an ordinary shovel or scoop.

My invention is not limited to the embodiment thereof hereinbefore described and illustrated in the accompanying drawings, but it may be embodied in various other forms within the nature of the invention as it is defined in the following claims. 70

I claim:—

1. An ash-sifter comprising a foraminous, shovel-like body provided with an elongated handle; a plurality of laterally separated, narrow supporting-members movably attached to the body near its forward end; and manually-operable means, extending to a point of convenient accessibility on the handle, for raising and lowering the supporting-members with respect to the body, 75 said members, when lowered, extending to a substantial distance below all other parts of the sifter so that they may engage a floor-surface and support the body at a sufficient distance above such surface to clear ashes 80 discharged thereon through the body; and said supporting-members being movable to a raised position in which they permit the body to rest substantially flat upon the floor-surface, to facilitate its use in the manner 90 of a shovel.

2. An ash-sifter having, in combination, a handle; a foraminous shovel-like body rigidly supported on the handle; a sheet-metal member pivoted, at one edge, to the 95 forward edge of the body and bent, at its ends, to provide side-walls and supporting-means extending beyond the side-walls; and manually-operable means for swinging said member alternatively into position to provide a lip and side-walls for the forward end of the body, or an end-wall and supports for the body. 100
